UNITED STATES PATENT OFFICE.

WILLIAM RAY DAVIS, OF MINNEAPOLIS, MINNESOTA, ASSIGNOR TO THE WILLIAM HOOD DUNWOODY INDUSTRIAL INSTITUTE, OF MINNEAPOLIS, MINNESOTA, A CORPORATION.

RADIOSIGNALING APPARATUS.

1,387,885.

Specification of Letters Patent. Patented Aug. 16, 1921.

Application filed March 9, 1918. Serial No. 221,569.

To all whom it may concern:

Be it known that I, WILLIAM R. DAVIS, a citizen of the United States, resident of Minneapolis, county of Hennepin, State of Minnesota, have invented certain new and useful Improvements in Radiosignaling Apparatus, of which the following is a specification.

The object of my invention is to provide 10 an apparatus by means of which radio or wireless signals can be produced for class room work corresponding substantially to the signals a radio operator would be required to receive in actual practice.

15 A further object is to provide an apparatus by means of which radio signals can be transmitted to any number of pupils, all of whom may receive the same signals.

20 A further object is to provide an apparatus of simple, inexpensive construction and one which can be easily and quickly installed in the radio instruction department of any industrial or technical school.

25 The invention consists generally in various constructions and combinations, all as hereinafter described and particularly pointed out in the claims.

In the accompanying drawings forming part of this specification,

30 Figure 1 is a diagrammatic view of the signaling apparatus embodying my invention,

35 Fig. 2 is a front elevation of the revolving disk device, showing its position with respect to the stationary magnets,

Fig. 3 is an edge view of the same.

In the drawing, 2 represents a motor of any suitable type and power, having a shaft 3 on which is mounted a disk 4. This disk 40 is preferably of steel and is provided with a series of peripheral notches 5 alternating with lugs or teeth 6. This disk is revolved at any desired speed. Mounted adjacent to the periphery of the disk are a series of magnets 7, substantially U-shaped and suitably spaced apart around the outside of the disk, with sufficient clearance between their poles and the periphery of the disk to allow freedom of revolution of the disk without contacting therewith. I have shown a few of these magnets at the bottom of the disk, but it will be understood there may be any desired number grouped around it.

One of the poles, as at A, has an insulated

conductor C wrapped thereon and in circuit 55 with the battery B through a suitable switch S. The conductor C passes from the pole of the first magnet to the corresponding pole of the next one and so on around the disk, a suitable number of coils of the conductor 60 being provided for each pole and from the pole of the last magnet the conductor extends to the battery so that the corresponding poles of the magnets are all in series 65 circuit and controlled by the switch S. The other poles of the magnets have independent conductors D wrapped thereon. Each of the conductors D has a sending key K therein and a series of receivers H are in circuit 70 with the conductors D and located at suitable tables, around which the radio students are seated. There may be any desired number of tables, according to the size of the revolving disk and the number of magnets and while the pitch or tone of the alternating 75 current produced by the revolution of the disk will be the same in all the circuits while the disk is revolving at a certain speed, the person controlling the key K in each circuit D increasing or decreasing the speed of 80 sending the signals, according to the capacity of the students in that circuit to receive them. Thus one group of students may be seated at a table where the signals are given very slowly, only a few words per 85 minute, the operator at the key regulating the speed of sending according to the ability of the students at the table with which his circuit is connected. Another table may be used for more advanced students, the signals 90 being sent faster and so on through the room until the student reaches a table where the signals have to be received with substantially the same speed as required in actual practice.

95 When the disk is stationary, it will be understood that the circuits D will be dead, but the revolution of the disk past the ends of the magnets will have the effect of varying the magnetism and thereby producing 100 an induced current in the circuits D, the tone or pitch depending upon the speed of revolution of the disk. The higher the speed, the sharper and higher the pitch of the apparatus will be. There may be any 105 desired number of the disks on the same shaft and a corresponding number of magnets may be provided for each disk, each

magnet being connected with an independent circuit in which a current is induced through the revolution of the disk.

I claim as my invention:

- 5 1. An apparatus of the class described comprising a series of U-shaped magnets, a winding on each pole of said magnets, the windings on one pole of each of said magnets being connected in series in an electric circuit, independent conductors connected with the other windings of said magnets and each having a sending key and a number of receivers therein, and a disk having a series of armatures mounted to revolve in the field of said magnets.
- 10 2. An apparatus of the class described comprising a series of U-shaped magnets, a winding on each pole of said magnets, the windings on one pole of each of said magnets being connected in series in an electric
- 15

circuit, independent conductors connected with the other windings of said magnets and each having a sending key and a number of receivers therein, and a disk having a series of armatures mounted to revolve in the field of said magnets.

3. An apparatus of the class described comprising a series of magnets, a winding on each pole of said magnets, the windings on one pole of each of said magnets being connected in series in an electric circuit, independent conductors connected in parallel with the other windings of said magnets and having sending keys and receivers therein, and means for revolving armatures in the field of said magnets.

In witness whereof, I have hereunto set my hand this 15th day of February 1918.

WILLIAM RAY DAVIS.
